UNITED STATES PATENT OFFICE.

CHRISTOPHER OFFENHAUSER, OF PHILADELPHIA, PENNSYLVANIA.

DESIGN FOR AN AUTOMOBILE BUMPER.

Application filed July 10, 1925. Serial No. 14,054. Term of patent 14 years.

To all whom it may concern:

Be it known that I, CHRISTOPHER OFFENHAUSER, a citizen of the United States, residing at Philadelphia, in the county of Philadelphia and State of Pennsylvania, have invented a new, original, and ornamental Design for Automobile Bumper, of which the following is a specification, reference being had to the accompanying drawing, forming part thereof.

Figures 1 and 2 represent respectively a top plan view and a front elevation of an automobile bumper showing my design.

I claim:—

The ornamental design for an automobile bumper, as shown.

CHRISTOPHER OFFENHAUSER.
